UNITED STATES PATENT OFFICE.

EDWARD A. FIELD, JR., OF GRAND RAPIDS, MICHIGAN, ASSIGNOR OF ONE-HALF TO
EDWARD A. FIELD, SR., OF OAK PARK, ILLINOIS.

HIGH-COMPRESSION INTERNAL-COMBUSTION ENGINE.

1,318,006.

Specification of Letters Patent.

Patented Oct. 7, 1918.

Application filed February 2, 1918. Serial No. 215,041.

To all whom it may concern:

Be it known that I, EDWARD A. FIELD, Jr., a citizen of the United States, residing at Grand Rapids, in the county of Kent and State of Michigan, have invented new and useful Improvements in High-Compression Internal-Combustion Engines, of which the following is a specification.

The present invention relates to high compression internal combustion motors and its object is, generally, to provide an improved motor of that general character; and more particularly, to provide means for delivering fuel to the cylinders of the engine in which the amount of charge and the time of delivery may be nicely regulated; and to provide an improved eccentric construction for regulating the time of delivery of the charge with respect to the compression 20 stroke of the piston.

These and any other objects appearing hereinafter are attained by, and the invention finds preferable embodiment in, the structure hereinafter described and illustrated by the accompanying drawings, in which:

Figure 1 is a transverse vertical sectional view of an engine constructed according to this invention;

Fig. 2 is a continuation of Fig. 1, showing the improved means for regulating the time of delivery of the fuel charge;

Fig. 3 is a side view of the mechanism shown in Fig. 2;

Fig. 4 is a vertical sectional detail taken on the line 4-4 of Fig. 1.

Engines of the same general type to which the present invention relates are frequently provided with means for delivery of the fuel charge under pressure against the pressure within the cylinders, while others are provided with a receptacle for receiving the charge in the head of the cylinder, the charge being forced out of said receptacle when the air in the cylinder is compressed, and when the compression reaches the ignition point the combustion takes place at once. The present invention relates to the latter specific type of engine but means are provided for opening ports in the fuel charge receptacle when the compression is higher than that normally required for effecting ignition. When the outlet ports of the fuel 55 receptacle are opened the compressed air

forces the charge out of said receptacle into the engine cylinder. The charge is highly heated or evaporated during the latter action and of course when it comes in contact with the compressed air almost complete combustion of the fuel takes place.

In the embodiment of the invention chosen for illustration by the drawings and for detailed description in the body of this specification, the cylinders 1 are provided with usual air inlet valves 2, corresponding to the mixture valve of the ordinary four-cycle engine in which gasoline or other highly volatile fuel is employed. The exhaust valve is of similar construction but not shown. The operating means for these valves is omitted from the drawing since it may be the customary connection to a cam shaft. A piston 3 of usual construction is shown in the cylinder 1.

The head of the cylinder is provided with a vertical bore 4 in which is mounted a cylindrical member 5 containing a fuel inlet channel 6. A passage 7 connects the channel 6 with a vertical passage 8 in which is slidable a reciprocating plunger 9 for forcing fluid from the passage 8 through a passage 10 leading to the interior of the fuel charge receptacle 11. Communication between passages 7 and 8 is closed by a check valve 12 during the down-stroke of plunger 9, and the outlet of passage 10 to the receptacle 11 is controlled by valve 13. The upper end of the stem 14 of valve 13 is surrounded by a coil spring 15 which is normally held compressed by the cup-shaped end 16 of a lever 17 which is pivoted at 18 and operated by a connection to the cam shaft not shown. This lever is rocked to relieve tension of spring 15 at the time of the down-stroke of plunger 9 when it is desired to deliver fuel to the receptacle 11. The outlet ports 19 of the receptacle 11 leading to the interior of cylinder 1 are controlled by a sleeve valve 20. This valve is in the form of a cylinder surrounding receptacle 11 and is cut away at its upper end to provide a pair of upstanding arms 21. These arms are pivotally connected to the inner end of the forked lever 22 in turn pivoted to a bracket 23 secured to the member 5. The outer end of lever 22 is connected to a pitman 24 which is reciprocated by means of a rotary eccentric 25, Fig. 2. With this construction, rotation of the eccentric 110

causes the rocking of lever 22 and consequently the reciprocation of the cylindrical valve member 20. The ports 26 of said valve member are thus alternately caused to 5 come into and out of registration with the outlet ports 19 of the fuel charge receptacle 11.

Inasmuch as the valve 20 moves transversely to the pressure thereon in opening 10 and closing, it will be seen that this valve is balanced as to gas pressures.

The particular construction to which this invention relates with respect to regulating the time of action of valve 20 is shown in 15 Figs. 2 and 3. The crank-shaft 27 carries a pinion 28 meshing with the gear 29 fast to a shaft 30. The eccentric 25 is loose on the shaft and angularly adjustable thereon with respect to the gear 29 but is normally 20 held in positive relation with the gear by means of an arm 31 integral with the eccentric. The outer end of this arm is pivotally connected to a lever 32 which is pivotally mounted on an eccentric 33 journaled on a 25 stub shaft 34 extending from the side of gear 29. Integral with the eccentric 33 is an arm 35 connected by a link 36 with a bell crank lever 37 pivotally mounted on ears 38 of gear 29. A universal joint 39 is provided 30 between the link 36 and bell crank lever 37. The opposite end of the bell crank lever is forked and has pins 40 extending into a grooved collar 41 slidably mounted on shaft 30. This collar is shiftable along the shaft, 35 in order to rock the bell crank lever, by means of a manually operated lever 42. With this construction, adjustment of lever 42 causes the rocking of the bell crank lever and consequently through the link 36 and arm 35 adjustment of eccentric 33 on the pin 34. The partial rotation of eccentric 33 results in bodily motion being imparted to the lever 32, the motion from this lever being transmitted through the arm 31 to the 45 eccentric 25. Thus the eccentric 25 is adjusted angularly with respect to the gear 29 with which it rotates and accordingly its action is advanced or retarded as desired with respect to the rotation of cam shaft 27. 50 In this manner the time of opening of valve 20 may be nicely adjusted.

In order that the heat of compression in the cylinder may be easily radiated to the fuel charge within the receptacle 11, the latter to increase its surface, is preferably ribbed as shown in Fig. 1.

The rocker arm 17, which serves to tension the operating spring 15 for valve 13, is provided with a shoulder 43 for bearing 60 against and actuating the stem 44 of inlet valve 2. It likewise carries a bent arm 45 bearing against a spring 46 secured to the operating arm 47 for the plunger 9. The pivotal point for the arm 47 is at its right-hand end, Fig. 1, and is adjustable by gov-

ernor, not shown, controlled eccentric 48, in order to automatically regulate the stroke of plunger 9 for the purpose of varying the amount of fuel delivered to receptacle 11.

In the operation of the device, during the 70 suction stroke the inlet valve 2 is opened and air only is drawn into the combustion chamber. The same mechanism, rocker arm 17, which opens the inlet valve also, through the bent arm 45 and lever 47, forces the plunger 9 downwardly, squeezing out a certain amount of fuel oil past the small puppet valve 13 into the chamber 11. Then when the main piston compresses the air into the cylinder and reaches the upper end of the 80 stroke, the sleeve or piston valve 20 is shifted to cause its ports to register with the ports 19 in the receptacle 11. The heat of compression causes the oil in this receptacle to vaporize and when communication is 85 opened between the receptacle and the combustion space the oil ignites forcing the working piston down. It will be understood that previous to the stroke of plunger 9 the head of the oil causes it to raise the check 90 valve 12 and enter the space below the plunger 9.

In case motor should stall while operator is absent, the cylinder (four-cylinder motor) whose inlet valve is open will have the tension relieved on the small spring which seats the fuel puppet valve. At the same time the fuel plunger is forced down and it presses against the small spring above the ball check valve, thus effectively sealing the 100 main cylinder from a possible flooding of oil.

The invention being intended to be pointed out by the claims severally, is not to be limited to or by details of construction shown or described.

I claim:

1. An internal combustion motor of the class described, comprising an engine cylinder and a fuel supply device consisting of a receptacle having an outlet port communicating with the interior of said cylinder, a valve balanced as to gas pressures and controlling said port, said receptacle having an inlet port, a valve for controlling said inlet port and means for moving the valves alternately for opening and closing said ports in succession.

2. An internal combustion motor of the class described, comprising an engine cylinder and a fuel supply device consisting of 110 a receptacle having an outlet port communicating with the interior of said cylinder, a valve controlling said port, said receptacle having an inlet port, a valve for controlling said inlet port and means for moving the 115 valves alternately for opening and closing said ports in succession, said means including a rotatable member having mounted thereon a valve operating eccentric, and means for angularly adjusting said eccentric 120 125 130

with respect to said rotatable member for the purpose of altering the relative time of action of the valves operated thereby.

3. An internal combustion motor of the 5 class described, comprising an engine cylinder and a fuel supply device, an outlet port for said fuel supply device communicating with the interior of said cylinder, a valve controlling said port, a rotatable member

and an eccentric mounted on said member for operating said valve, and means for angularly adjusting said eccentric with respect to said rotatable member for the purpose of changing the time of action of said valve.

In testimony whereof I have hereunto set 15 my hand at Grand Rapids, Michigan, this 29th day of January, 1918.

EDWARD A. FIELD, JR.
